SAMUEL S. BENT, OF PORTCHESTER, NEW YORK.

Letters Patent No. 85,557, dated January 5, 1869.

IMPROVED DOG-KENNEL OR HOUSE.

The Schedule referred to in these Letters Patent and making part of the same.

To all whom it may concern:

Be it known that I, SAMUEL S. BENT, of Portchester, in the county of Westchester, and State of New York, have invented, made, and applied to use a certain new and useful Improvement in Houses for Dogs, &c.; and I do hereby declare the following to be a full, clear, and exact description of the said invention, reference being had to the annexed drawing, making part of this specification, wherein—

Figure 1 is a front elevation of said house, with the cornice removed on one side to show the roofing;

Figure 2 is a sectional plan of the front portion of said house; and

Figure 3 is a section at the line *x x*.

Similar marks of reference denote the same parts.

Houses for dogs are usually of an unsightly appearance, and to ornament a wooden dog-house with carved work would be costly, and dog-houses made complete at a manufactory, and transported a distance to the place where they are to be used, would be costly in freight, on account of the bulk.

The same remarks apply, to a certain extent, to wren and other bird-houses.

The object of my invention is to provide a neat, cheap, durable, and strong metal front to the dog-house, that will be ornamental, and can be used with wooden or metal sides and roof, and can be connected to the same with facility, so that the dog-house can be taken apart for transportation, or the metal portion can be easily connected with wood-work that could be built in almost any country place where the house is to be used, thus insuring strength and neatness of appearance.

In the drawing, *a* is the metal front, formed with flanges, 1 1, at the vertical angles, that receive screws for connecting the front *a* with the sides *b b*. These flanges and screws, coming on the inside, are not noticeable.

The upper part of the front, *a*, is formed with the flanges 2, that project beneath the roof-boards or covering *c*, and are screwed thereto, as seen in fig. 3.

The said flanges 2 aid in producing the appearance of a cornice, and this ornamental appearance may be still more increased by the ornamental metallic strips *d d*, fastened upon the projecting ends of the roof-boards.

A similar front to the front, *a*, may be used on the opposite part of the house, or a closed end or back may be employed.

In the front, *a*, is an opening, *e*, forming an ornamental doorway, and *f* is a ventilator in the upper part of the front, forming also an ornament.

g g are rings, to which the chain or hitching-cord for the dog may be attached.

What I claim, and desire to secure by Letters Patent, is—

The metallic front, for a dog or other small house, formed with the doorway, and flanges for attaching the sides and roof, as and for the purposes set forth.

In witness whereof, I have hereunto set my signature, this 13th day of June, A. D. 1868.

SAMUEL S. BENT.
